UNITED STATES PATENT OFFICE.

JOSEPH C. COULOMBE, OF DRACUT, MASSACHUSETTS.

SIGNAL HORN.

Application filed November 17, 1919. Serial No. 338,468.

To all whom it may concern:

Be it known that I, JOSEPH C. COULOMBE, a citizen of the United States, residing at Dracut, county of Middlesex, Commonwealth of Massachusetts, have invented certain new and useful Improvements in Signal Horns, of which the following is a specification.

My present invention relates to certain improvements in horns and particularly to diaphragm horns especially of the motor driven type used by automobiles.

One of the greatly desired features in horns of this type is rapid vibration to secure proper pitch and this is intimately coupled with the factor of wear. My invention therefore contemplates a horn structure in which an extremely rapid vibration may be quickly set up and sustained with a minimum of shock and wear to the mechanical parts.

In carrying out my invention I employ an axial shaft, that is to say, a shaft lying in or substantially in the axis of the diaphragm. The objections to so disposing a shaft lies in the apparent conflict of multiple contact in the rotor and concentricity of diaphragm impact. I am able to accomplish the desired features of both axial alignment and central impact by a simple arrangement of contacting elements by which impacting vibration is multiplied. At the same time my invention lends itself to advantageous structure, efficient, symmetrical, economical and durable. Throughout the specification and drawings like reference numerals are employed to indicate corresponding parts, and in the drawings:

Fig. I is a side view partly in section of a horn in accordance with my invention.

Fig. II is a rear view of the horn cup.

Fig. III a fragmentary portion of the diaphragm showing the cam button stem opening.

Fig. IV a side elevation of front cam face and rear view respectively of the cam button, and

Fig. V a front face and fragmentary side section of the rotary shaft head.

In the form of horn shown as illustrative of my invention I provide a body portion consisting of a motor casing 1 having bearing portions 2 and 3 on each side thereof in axial alignment with the armature shaft. This armature shaft is continued as the main rotor shaft 4 which finds bearings in 2 and

3 at 5 and 6 which are oiled at 7. One end of the shaft 4 is slightly concaved as at 4¹. Against this concavity rests a spherical follower 8 held in place by a spring 9 adjustable by a plug 10 screwed into the extension 2 and held by a lock nut 11 threaded on the plug.

On the inner end of the shaft 4 is a rotor member 12 having cam teeth 13. Within a shell 15 mounted on the end of the portion 3 is a diaphragm casing within which is a diaphragm 16. The diaphragm 16 is fitted at its center with a button 17 having cam teeth 18. The stem 19 is slightly flattened as indicated at 19¹, Fig. IV, and fits through a similarly shaped opening 16¹ in the diaphragm 16, and also through a similar opening in a collared washer 20¹. A spring 20 is disposed between this collared washer and the shouldered head of an adjustable stem 21 which is threaded through a reinforced yoke 22 which is set within the shell 15 of the diaphragm casing and projects slightly within the horn member 24 which is also attached to that casing.

Upon the rotation of the shaft 4 in the motor 1 the rotor head 12 through its following spring 9 works yieldingly against the button 17. The cam teeth of the rotor head and the button are one of an odd number and one of an even number. In the form shown the rotor head has two cam teeth 13, while the button has five of such teeth. These numbers may be varied as long as the odd and even relation is preserved so as to multiply the contact and thus increase the speed of vibration. The diaphragm 16 may therefore be set immediately into a high speed vibration giving the desired pitch to the horn.

It will be noted that the shaft 4 is disposed axially of the diaphragm and symmetrically on the central axis of the horn. This not only makes a very convenient and satisfactory structure, strong and pleasing in appearance but as in the form shown gives a very high efficiency.

Through the relation of the odd and even numbers of the cam teeth it is possible with this central axial alignment to get the high vibration desired. The axial yielding of these aligned members insures not only prompt engagement and release, but also introduces a factor of great saving in wear.

Various modifications may obviously be made in the type of horn as well as in the

form of structure and arrangement of the several parts all such modification and variation may be made without departing from the spirit of my invention if within the 5 limits of the appended claims.

What I therefore claim and desire to secure by Letters Patent is:

1. In a horn, a diaphragm, a rotor shaft in central axial alinement therewith, a 10 spring pressed follower behind said shaft, and a spring pressed follower on the opposite side of said diaphragm and alined with said shaft.
2. In a horn, a diaphragm, a rotor shaft in central axial alinement therewith, an adjustable spring pressed follower behind said shaft, and an adjustable spring pressed follower on the opposite side of said diaphragm and alined with said shaft.
3. In a warning signal, a diaphragm casing having a sound-emission opening in a wall thereof, a horn having its inner end seated in said opening, and a perforated member disposed within said horn and adjustably clamping said horn in said position.
4. In a warning signal, a casing having a sound-emission opening in a wall thereof, a perforated member set across said opening with its inner edge seated against the 30 inner face of the casing wall adjacent said opening, and means adjustably clamping said member in said relation.
5. In a warning signal, a casing having a sound-emission opening in a wall thereof,

an outwardly disposed perforated member 35 set across said opening with its inner edge seated against the inner face of the casing wall adjacent said opening, and a spring-tensioned follower adjustably clamping said member in said relation.

6. In a warning signal, a diaphragm casing having a sound-emission opening in a wall thereof, a perforated member set across said opening with its inner edge seated interiorly of the casing wall adjacent said opening, a follower adjustable in said member, a diaphragm in said casing, and a spring interposed between said follower and the diaphragm for clamping said member in said relation.

7. In a warning signal, a diaphragm casing having a sound-emission opening in a wall thereof, an outwardly bowed perforated member set across said opening with its inner edge seated interiorly of the casing wall adjacent said opening, said member having a bearing, a follower adjustable in said bearing, a diaphragm in said casing, a button on said diaphragm alined with said follower, and a spring interposed between 60 said follower and the diaphragm button for clamping said member in said relation.

In testimony whereof I affix my signature in presence of two witnesses.

JOSEPH C. COULOMBE.
